(57) **CLAIM**

The ornamental design for an interior bottom portion for a compartment or an automobile trunk, as shown and described.

DESCRIPTION

FIG. 1 is a top perspective view of an interior bottom portion for a compartment or an automobile trunk.

FIG. 2 is a side elevation view of the interior bottom portion of FIG. 1; and,

FIG. 3 is a front elevation view of the interior bottom portion of FIG. 1.

The features shown in dashed lines form no part of the claimed design.

The automobile trunk interior bottom portion in use is visible with the decklid raised or otherwise moved from its closed position.
